UNITED STATES PATENT OFFICE

EDGAR STROKE, OF LOS ANGELES, CALIFORNIA

ELECTRIC LANTERN

Application filed December 9, 1926. Serial No. 153,627.

This invention relates to a lantern especially adapted for use in and about railroad yards and embodying an incandescent electric lamp, reflectors, a storage battery, and a switch for controlling the connection between the lamp and battery.

The invention has for one of its objects to provide a lantern of the character stated wherein the reflectors shall be of such construction and so relatively arranged as to enable the provision of a comparatively bright light from a lamp of comparatively low power consumption.

A further object of the invention is to provide a lantern of the character stated wherein the storage battery shall be of the type having a semi-solid electrolyte and wherein provision shall be made for the recharging of the battery without removing it from the lantern.

A further object of the invention is to provide a lantern of the character stated which shall embody a construction adapted to prevent the short circuiting of the switch or the short circuiting of the terminals of the battery by water.

The invention is hereinafter more fully described and claimed, and illustrated in the accompanying drawing, wherein:

Figure 1 is a view in side elevation of an electric lantern embodying my invention,

Figure 2 is a sectional view taken on a plane extending vertically and centrally through the lantern,

Figure 3 is a detail sectional view of the switch,

Figure 4 is a detail sectional view taken on the plane indicated by the line 4-4 of Figure 3, and

Figure 5 is a detail view of a slight modification of the lamp.

Referring in detail to the drawing, in the several views of which like reference characters denote like parts, 1 designates the base, 2 the globe, 3 the cap, and 4 the globe guard of the lantern. A wire stand 5 is secured to the base 1, and a bail 6 is pivoted to the guard 4.

The lantern is provided with a horizontally disposed concave reflector 7 which is

carried by the upper end of the conical top wall 8 of the base 1, and an inverted conical reflector 9 which is located above and axially aligned with reflector 7. The reflector 9 is secured to the cap 3. A socket 10 is carried by the reflector 7 for the reception of an incandescent electric lamp 11 of low power consumption. One end of the filament of the lamp 11 is electrically connected to the wall 8, and the other end of the filament is electrically connected to the spring strip 12 which is arranged within the base 1 and is secured to one of the lateral walls of the base by a bolt 13. A storage battery 14 is arranged within the base 1 and is of that type having a semi-liquid electrolyte. The negative terminal 15 of the storage battery 14 is connected to the wall 8 by a lead 16, and the positive terminal 17 of the storage battery is connected to a switch 18 by a lead 19. The switch 18 is slidably mounted in a slot 20 formed in the base 1 below the bolt 13, and is adapted to be moved into and out of contact with the lower end of the strip 12. This end of the strip 12 extends below the bolt 13 which is insulated from the base 1 by a bushing 21. The switch 18 comprises a body 18^a of insulating material which is mounted in the slot 20 and provided at its inner end with a strip 18^b which closes the slot when the switch is in either of its on or off positions. The body 18^a is provided at its outer end with a head or knob 18^c to permit it to be readily moved into on or off position. The switch 18 also comprises a metal block 18^d which is secured to the strip 18^b and which has its inner face inclined to permit it to be readily moved into contact with the lower end of the strip 12. The switch 18 is held against casual movement by a leaf spring 22 which is mounted on the body 18^a between the base 1 and head or knob 18^c and which contacts at its free ends with the base. The storage battery 14 is held out of contact with the lower end of the strip 12 by a bracket 23. The side wall 24 of the base 1 is removably secured in place to permit the application and removal of the storage battery 14. The wall 24 is provided with knuckles 25 and the top and bottom walls of the base 1 with knuckles 26 for the

reception of pins 27 through the medium of which the wall 24 is secured in place. The wall 24 is provided with an opening 28 in alinement with the positive terminal 17 of the storage battery 14 so as to permit the storage battery to be recharged without removing it from the base 1. A cover 29 which is pivoted as at 30 is provided for the opening 28 and is adapted to be maintained in position to close the opening by gravity.

When the lamp 11 is burning, the rays therefrom are directed by the deflector 7 onto the reflector 9 which directs them radially in all directions from the lantern. The construction and relative arrangement of the reflectors are such as to produce a comparatively bright light from a lamp of comparatively low power consumption. As the lamp 11 is of low power consumption the storage battery 14 will last for a comparatively long time, and due thereto the lamp may be kept lit for any desired or required length of time. As the slot 20 and opening 28 are always closed, and as the bottom wall of the base 1 is supported by the base 5 out of contact with any wet surface on which the lantern may be placed, there is no danger of water accumulating in the base 1 and short circuiting the switch or the battery. The lamp is of simple and inexpensive construction, and it may be maintained in operation at small cost. To prevent the wall 24 from short circuiting the battery terminals 15 and 17, a strip of insulation 24^a is secured to this wall against the inner side thereof.

As shown in Figure 5 the lantern may be provided with a white lamp 11 and a red lamp 11^a, and when it is provided with these lamps it will be provided with two switches so that either may be lit as conditions require.

What is claimed is:—

An electric lantern comprising a metallic base having an elongated slot therethrough, a spring conductor arranged within the base, insulating means securing the conductor adjacent one of its ends to the base, said means spacing said end of the conductor from said wall, said end extending beyond said means and in spaced relation to said base, an insulating member within the base covering said slot at all times and having an element passing through said slot and slidably associated with the base, and a metal contact block within the base carried by said member and movable thereby into and out of contact with said conductor end.

In testimony whereof I affix my signature.
EDGAR STROKE.
